UNITED STATES PATENT OFFICE

SAMUEL B. FERGUSON, OF HARLINGEN, TEXAS

RAILROAD TIE

Application filed June 10, 1930. Serial No. 460,208.

The present invention relates to railroad ties, and its object is to provide a metallic device of this character having means for securely holding rails in position thereon without the necessity of utilizing spikes or other like fastening devices such as are ordinarily employed.

Another object is to provide a combined rail support and holding device adapted to cooperate with the tie for fastening the rail thereto.

A still further very important object of the invention resides in the provision of a railroad tie of this nature which is simple, inexpensive to manufacture, strong and durable, thoroughly efficient and reliable in use and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawings:

Figure 1 is a top plan view of a pair of tie structures embodying the features of my invention.

Figure 2 is a sectional view taken substantially on the line 2—2 of Figure 1,

Figure 3 is a sectional view taken substantially on the line 3—3 of Figure 1,

Figure 4 is a sectional view taken substantially on the line 4—4 of Figure 1,

Figure 5 is a sectional view taken substantially on the line 5—5 of Figure 4, and

Figure 6 is a perspective view of one of the wedge keys.

Referring to the drawings in detail it will be seen that the numeral 1 denotes a metallic tie having side walls 2 extending upwardly from its base, said walls being straight and parallel. The ends of the wall are preferably beveled as is indicated at 3 and seats 4 are formed on the upper ends of these beveled portions and are overhung by tongues 5 which are integral with the side walls and are disposed at such an angle to the seat as to overlap and fit snugly over the inner base flanges of rails 6. Supporting blocks 7 form-

ed of metal are located within the tie and the thickness of these blocks is equal to the distance from the bottom of the tie to the seat 4.

It is therefore obvious that when the blocks are in position adjacent the seat they will assist said seats in supporting the rails mounted therein. Each block has an inwardly extending ear 8 adapted to overlap the outer base flanges of the rail 6. Wedge shaped means 9 extend horizontally and transversely through the end portions of the side walls 2 and through openings in the blocks 7 to securely hold the same in place and these wedge shaped keys are held against displacement by cotter pins 10 or the like.

Transversely extending ribs 11 are formed integrally on the bottoms of the tie to be embedded in the road bed.

In using the tie herein described, the same is placed in the road bed and the blocks 7 are placed in the ties. The rails are then placed under the tongues 5 to be seated on the seat 4 and the blocks 7. The blocks 7 are then driven inwardly and the wedge keys are then driven in place.

On the bottoms of the blocks 7 are longitudinally extending channels 15 to allow proper drainage of the water from the tie.

It is thought that the construction, utility and advantages of this invention will now be clearly understood by those skilled in this art without a more detailed description thereof.

The present embodiment of the invention has been described in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. The combination with a channelled metallic tie having rail engaging tongues integral therewith for engaging the inner flanges

of rails, of rail supporting blocks slidable endwise in the tie, ears integral with the blocks for engaging the outer flanges of rails, wedge keys extending through openings in the sides of the tie and in the block for holding the blocks against movement when engaged with the rail.

2. The combination with a channelled metallic tie having rail engaging tongues integral therewith for engaging the inner flanges of rails, of rail supporting blocks slidable endwise in the tie, ears integral with the blocks for engaging the outer flanges of rails, wedge keys extending through openings in the sides of the tie and in the block for holding the blocks against movement when engaged with the rail, and ribs integral with the bottom of said tie.

In testimony whereof I affix my signature.
SAMUEL B. FERGUSON.
